United States Patent Office

Des. 198,801
Patented Aug. 4, 1964

198,801

EXERCISING DEVICE

Duane E. Mitchell, Shandon Rte., Paso Robles, Calif.

Filed Mar. 19, 1963, Ser. No. 74,035

Term of patent 14 years

(Cl. D34—5)

The single figure of the drawing is a perspective view of an exercising device embodying my new design.

The dominant features of my new design are shown in solid lines.

I claim:

The ornamental design for an exercising device, substantially as shown and described.
